TRIGGER MECHANISM OF AUTOMATIC GUNS

Louis Stange, Sommerda, Germany, assignor to
Rheinmetall-Borsig Aktiengesellschaft, Dusseldorf, Germany, a corporation of Germany

Application October 10, 1936, Serial No. 105,095
In Germany February 2, 1934

5 Claims. (CL. 42—69)

In general, the trigger mechanism of automatic guns operates in such manner that when the trigger moves into its normal position upon release of finger pressure upon it, a sear lever which, when firing is interrupted, holds the striking mechanism (the breech block or the striking pin) in the cocked position, is simultaneously moved into the position to effect this holding action.

10 In a development of such mechanism an additional detent has been provided to ensure that the sear lever is permitted to operate only after the trigger has been released and again pressed, in a non-operative movement, backwards.

15 In contradistinction to this, by the present invention a detent for the sear lever is arranged in such operative connection with the parts of the gun which operate during firing that it is uninfluenced by a return movement of the trigger after the latter has been released and remains in the position in which it retains the sear lever, and only releases the sear lever when the correct position of rest is reached by the striking mechanism. The sear lever then moves, but it is 20 can only complete its movement if it has the time and opportunity to enter the whole surface of its retaining projection into the striking mechanism which is to be arrested. Heavy wear of the retaining projection of the sear lever as a result 25 of the breech block surface sliding along its face, and an imperfect seating of the lever, which latter action may lead to dangerous unintended shooting, are thus avoided. Preferably, in addition to a mere release of the sear lever, it is 30 simultaneously led positively into the retaining position by the firing movements of the breech parts to be retained.

In a further feature of the invention means are provided positively to effect the movement 40 of the sear lever to its holding position under the influence of the moving parts of the breech mechanism.

The invention is illustrated by the accompanying drawings, which show two examples of a 45 trigger mechanism embodying the invention together with certain parts of the gun and in which—

Figs. 1—4 show one example of a trigger mechanism in consecutive positions of operation;

50 Of these figures Fig. 1 is a diagrammatic view in which the trigger parts are in a position in which the striking mechanism is retained by the sear lever and the trigger is in a position of rest; Fig. 2 is a similar view showing the parts in a

position in which the sear lever is withdrawn by pulling back the trigger;

Fig. 3 shows the position in which the trigger is released to its original position;

Fig. 4 shows the position shortly before the 5 striking mechanism again snaps back into the position of Fig. 1;

Figs. 5 and 6 show another example in which the trigger catch is transferred positively into the retaining position.

10 In the trigger guard *a*, which is fixed to the gun stock, the trigger *b* is mounted in known manner on a pin *b*₁ so as to be pivotable against the pressure of a spring-urged bolt *b*₂ which maintains the trigger in its position of rest or 15 returns it thereto. By means of its nose *b*₃ the trigger *b* can rotate from its retaining position the sear lever *d* which engages, for example, with the breech block *c* to retain the latter in its cocked position. The lever *d* can be held out of 20 its retaining or holding position by pressing back the trigger *b*. On a recessed part of the top of the trigger *b* a release pawl *e* is pivoted on a pin *b*₄. The motion of the pawl *e* is limited on one side by a nose *e*₁ and on the other side by a 25 bridge piece *f*₁ which projects into a recess formed in the trigger *b*. The bridge *f*₁ is part of a detent *f* which is pivotally mounted on a pin *f*₂ in a recessed part of the trigger guard. A spring *f*₃ supported by the trigger guard tends to rotate 30 the detent *f* so as to cause a retaining nose *f*₄ to overlap a retaining projection *d*₃ on the sear lever *d* when the latter is withdrawn from engagement with the breech block.

35 By pressing the trigger *b* back, the sear lever *d*, which holds the breech block *c* in the cocked position (see Fig. 1), and pawl nose *d*₁, are rotated away from the grooved part *c*₁ of the block. The pawl *e* is simultaneously pulled 40 downwards and is then rotated by the bridge piece *f*₁ which bears on the rear surface of the pawl *e*, this movement being caused by the action of the spring *f*₃ which bears on the detent *f*. This rotation of the pawl *e* continues until its nose *e*₁ bears on the upper surface of the 45 trigger. The movement of the pawl *e* is sufficient to enable the detent *f* to move forward until its nose *f*₄ overlaps the projection *d*₃ on the sear lever *d* (see Fig. 2). The sear lever *d* is thus prevented from moving out of the withdrawn 50 position not only by the trigger, but also by the detent *f*. When the trigger *b* is released, the detent *f* remains in the retaining position (see Fig. 3) and by the return of the trigger *b* the pawl *e* is raised into the path of the breech 55

block *c*. When, then, the breech mechanism moves into position to bear on the pawl *e*, if it is not already in such position, the pawl *e* will be moved until its rear surface bears on the 5 bridge piece *f*₁ of the detent *f* when it will press the latter back, against the action of the spring *f*₂, out of the position in which it retains the sear lever *d*. The latter can now move upwards 10 under the action of its spring *d*₂ into position to retain the breech block *c* cocked (see Fig. 4). By appropriate synchronization of the co-operative parts, the lever *d* when released by the nose *f*₄, will always find above it the grooved part 15 *c*₁ of the breech block *c* with which it engages and so it brings into such engagement the whole of the surface of the retaining nose *d*₁.

While in the example of Figs. 1-4 the moving of the sear lever *d* into the position in which it retains the striking mechanism *c* is effected by 20 the action of a spring, in the example of Figs. 5 and 6 it is effected positively in dependence on the shifting of the pawl *e*. Thereby any possible rebound of the sear lever *d* which in the retaining position bears, for example, on the gun 25 housing (as at *g*, Fig. 6), is avoided. The spring *d*₂ can in this case be dispensed with.

For positively controlling the engagement of sear lever *d* with the breech block, the pawl *e* has an arm *e*₂ which, when the lever *e* is shifted, 30 engages the end of the lever *d* and rotates it into the retaining position (see Fig. 6).

I claim:

1. Trigger mechanism for automatic firearms having a breech block carrying a striking device, 35 comprising a trigger, a sear lever for holding the striking device in cocked position said sear lever being arranged to be retracted from said device by actuation of the trigger, a detent cooperating with the sear lever to hold it in retracted position, and means influenced by the breech block 40 after actuation of the trigger to release said sear lever for return to its breech block retaining position only when the sear lever and the striking device are in correct relative position for effective engagement with each other.

2. Trigger mechanism for automatic firearms having a breech block carrying a striking device, comprising a trigger, a sear lever for holding the striking device in cocked position said sear 50 lever being arranged to be retracted from said device by actuation of the trigger, a detent cooperating with the sear lever to hold it in retracted position, and means influenced by the breech block after actuation of the trigger to release said sear lever for return to its breech block retaining position only when the sear lever and the striking device are in correct relative position for effective engagement with each other.

position for effective engagement with each other, said means including a pawl pivoted on the trigger and adapted to move into the path of the breech block after the trigger is actuated, and a bridge piece on said detent cooperating with 5 said pawl in its ensuing contact with the breech block to effect said release.

3. Trigger mechanism for automatic firearms having a breech block carrying a striking device, comprising a trigger, a sear lever for holding the 10 striking device in cocked position said sear lever being arranged to be retracted from said device by actuation of the trigger, a detent cooperating with the sear lever to hold it in retracted position, means influenced by the breech block 15 after actuation of the trigger to release said sear lever for return to its breech block retaining position only when the sear lever and the striking device are in correct relative position for effective engagement with each other, and means actuated by the breech block for positively 20 restoring said sear lever into engagement with the striking device.

4. Trigger mechanism for automatic firearms having a breech block carrying a striking device, comprising a trigger, a sear lever for holding the striking device in cocked position said sear lever being arranged to be retracted from said device by actuation of the trigger, a detent cooperating 25 with the sear lever to hold it in retracted position, means influenced by the breech block after actuation of the trigger to release said sear lever for return to its breech block retaining position only when the sear lever and the striking device are in correct relative position for effective 30 engagement with each other, and an arm for positively restoring the sear lever into engagement with the striking device.

5. Trigger mechanism for automatic firearms having a breech block carrying a striking device, comprising a trigger, a sear lever for holding the striking device in cocked position, said sear lever being arranged to be retracted from said device by actuation of the trigger, a detent cooperating 40 with the sear lever to hold it in retracted position, means influenced by the breech block after actuation of the trigger to release said sear lever for return to its breech block retaining position only when the sear lever and the striking device are in correct relative position for effective 45 engagement with each other, resilient means normally urging said detent towards the sear lever, and means actuated by the breech block for restoring said lever into engagement with the striking device.

LOUIS STANGE.
